WASTE BASKET

Stig Gustav Nils Reinhold Nilsson, P.O. Box 25,
Kattarp, Sweden

Filed Jan. 14, 1971, Ser. No. 106,637

Term of patent 7 years

Int. Cl. D7—05

U.S. Cl. D7—193

Fig. 1

Fig. 2

Fig. 4

Fig. 3

Fig. 5

Fig. 6

Fig. 7

FIG. 1 is a front perspective view of a waste basket embodying my new design;

FIG. 2 is a side elevational view;

FIG. 3 is a fragmentary vertical sectional view on a larger scale taken on the line III—III of FIG. 6 with the bottom flap in its lowermost position;

FIG. 4 is a view similar to FIG. 3 but in a partly folded-up position;

FIG. 5 is a rear elevational view;

FIG. 6 is a top plan view with the lid removed; and

FIG. 7 is a bottom plan view.

I claim:

The ornamental design for a waste basket, substantially as shown.
